UNITED STATES PATENT OFFICE.

FREDERICK J. LUEBBERT, OF SAN FRANCISCO, CALIFORNIA.

HANGAR FOR AERIAL VEHICLES.

Application filed January 26, 1922. Serial No. 531,873.

To all whom it may concern:

Be it known that I, FREDERICK J. LUEBBERT, citizen of the United States, residing at San Francisco, in the county of San Francisco, State of California, have invented a new and useful Improvement in Hangars for Aerial Vehicles, of which the following is a specification in such full and clear terms as will enable those skilled in the art to 10 construct and use the same.

This invention relates to the construction of a hangar for aeroplanes and dirigible air ships in which the entire inside of the hangar will be free from supporting poles and guys, 15 all of the covering structure being supported from the outside by means of suitable masts.

This invention relates to a hangar which is an improvement upon the structure dis- 20 closed in United States Letters Patent No. 1,313,547, dated August 19, 1919, to W. M. Luebbert.

Another object of the invention is to provide a support for the covering structure 25 which is capable of carrying either a sheet metal covering or a canvas covering as may be desired.

Another object of the invention is to provide a cable truss with stiffening bars to 30 make it more rigid than it would be were it composed entirely of tension members.

Another object of the invention is to provide a series of openings in the covering 35 structure which will allow the escape of air during storms to prevent a too great strain upon the entire structure.

Another object of the invention is to provide rounded ends and sloping sides as well 40 as a sloping roof whereby the structure will offer less resistance to the air during storms than would a structure with square ends and vertical sides.

Another object of the invention is to produce a hangar which can be transported 45 from place to place in small units not to exceed the capacity of the ordinary five-ton army truck.

Another object is to produce a supporting structure for the hangar covering which is 50 capable of being set up and taken down independently of the covering thereby making it possible to put the covering in position with the minimum of effort and with unskilled labor.

55 Other objects of the invention will appear as the description proceeds.

An embodiment of the invention is shown in the accompanying drawings in which the same reference numeral is applied to the same portion throughout, but I am aware 60 that there may be modifications thereof.

Fig. 1 is a perspective view of the masts and bracing without the covering.

Fig. 1^a is a side elevation of the complete structure, showing a structure with a longer 65 span between the masts than the perspective view.

Fig. 2 is an end view of the structure with some of the cables removed and with the covering at one end removed. 70

Fig. 3 is a detail view of one of the anchor bolts used for supporting the masts.

Fig. 4 is a plan view of the complete hangar.

Fig. 5 is a side elevation on an enlarged 75 scale of one of the side trusses.

Fig. 6 is a plan view of one of the overlapping side plates looking from the inside.

Fig. 7 is an outside plan view of one of the overlapping cover plates.

Figures 8 and 9 are detail views of the clamp washers with raised portions for connection to one of the cables.

Figures 10 and 11 are detail views of one of the flat clamp washers used for holding 80 the metal sheet edges in place.

Fig. 12 is a side elevation of one of the clamps used, the lead washer for preventing leakage being shown thereon.

Fig. 12^a is a perspective view of the double cable clamp used.

Figures 13 and 14 are respectively a side elevation and sectional view of a portion of the roof of the hangar showing the detachable doors for reducing the wind pressure. 85

Fig. 15 is a plan view of one of the masts showing the flange for connecting the cables and braces thereto.

Fig. 16 is a side elevation of the upper 100 portion of one of the masts.

Fig. 17 is a side elevation of an intermediate portion of one of the center masts, and

Fig. 18 is a sectional view of one of the 105 bracing members extending from the outer mast to the central mast.

This hangar has two sets of tubular masts 1 to 6 inclusive. The masts 2 and 5 have three sets of flanges, while the masts at the outer corners of the hangar have two sets of flanges.

These flanges are constructed as illus-

trated in Figure 16. The separate parts of the tubular masts each have flanges at their ends as shown at 7 and 8, said flanges have suitable perforations to receive bolts or 5 shackles to connect them to the next adjacent tubular member.

Intermediate the ends of the mast the flanges are bolted together as illustrated at 10 the lower portion of Figure 16, a plate 9 10 being inserted between the flanges 7 and 8 for the purpose of carrying the holes for securing the guy wires and cables to the mast; also for securing suitable bracing when required.

15 Each of the corner masts is provided with an outrigger as indicated at 10 to 13 inclusive. These outriggers are suitably braced by means of cables 14 and 15 connected to the top and lower portion of each mast. 20 The corner posts are also connected to the longer center posts by means of heavy braces 16 to 19 inclusive which are inclined on substantially the same slope as the slope of the roof of the hangar. The corner masts 25 are connected by four cables 20 to 23 inclusive, two of which cables are also suitably connected to the masts 2 and 5. A cable truss consisting of the longitudinally extending cables 25, 26, 27, compression 30 members 28, 29, 30, diagonal bracing 31, 32 and vertical cable bracing 34, 35, 36 connecting the upper cable 25 to the intermediate cable 26.

35 The result of the foregoing construction is that there is a tension truss suspended from the two center posts 2 and 5, the upper member of said truss being more or less catenary shaped. These two center masts are braced against movement longitudinally 40 of the hangar by means of two cables 37, 38 at each end.

Each of the corner posts in pairs is provided with a tension truss consisting of the cables 23, 39, 40 and 21, 41, 42. The cables 45 40, 41 lie in a horizontal plane and are connected at their ends to the outriggers attached to the corner masts. The cables 39, 42 are attached to the upper portion of the corner masts and swing downwardly therefrom and by reason of the strain on the cross cables 43 to 47 inclusive which are attached at an intermediate point to said cables 39, 40, and at an intermediate point to the cables 23, 21 their ends being attached 50 to the cables 40, 41 produce a tension truss capable of holding the sides of the hangar straight and also capable of preventing the eaves from dropping down.

55 The corner masts are each braced by cables 48, 49, and two cables 50, 51 are connected to each outrigger and to suitable anchorages to prevent the outriggers from being displaced. In order to give additional stiffness to the side trusses formed, each 60 corner mast has two bracing cables 52, 53

connected to its upper end and to the cable 23, and each outrigger has a bracing cable 54 connected to its outer end and to the cable 23.

Inside the roof the center truss is also provided with bracing cables 55, 56 which are connected at their upper ends to the cable 27 under the compression members 28, 30, and at their lower portion to each of the masts 2 and 5.

70 Where the cables are anchored in the ground they are connected to a rod 60 having a suitable anchor 61 at its lower end, which anchor is placed at the bottom of a hole in which suitable rubble is tanked.

75 Wherever two cables cross each other suitable double cable clamps 63 are used to connect the cables together, said cable clamps being illustrated in Figure 12^a, and which consist of a plate 64 having two short horns 80 65, 66 and to which the two cables are secured by means of the U-bolt 67.

85 At the ends of the structure illustrated in Figure 1, the cables are arranged to pass from the top of the center masts downwardly to anchorages illustrated in Figure 1^a and as shown at 67', 68, while other cables 69, 70, 71 extend from an intermediate portion of the mast to the longer cable bracing 90 for the purpose of supporting the roof.

95 The center bracing cables 67' at each end are very heavy cables and in order to properly anchor them there is provided the bridle anchorages consisting of a series of pulleys 72 on the ends of short cables 73, the arrangement being such as to provide 100 after the short cables have passed over the pulleys 72 for anchorages at 74 to 79 inclusive, thereby increasing the holding power of the anchorages without increasing 105 their size.

110 The covering for the hangar consists of a plurality of metal sheets 80, said metal sheets being of considerable size and arranged to overlap one another at their edges sufficiently to shed water. These metal plates lie on the several cables of which there are a sufficient number of supporting cables such as are shown in Figure 6, added to the structure shown in Figure 1 to produce the necessary supporting cables to correspond with the size of the plates used, for example: Assuming the cable 45 to be shown in Figure 6, there would be connected to it two longitudinally extending cables 115 81, 82 to support the edges of the several plates, and a smaller central cable 83 to support the plates along their longitudinal center. The longitudinal cables would in turn have their cables 84, 85 connected thereto and to other cables of the system.

120 While the cables are connected together by means of the double clamps shown in Figure 12^a, the plates are connected to the cables by means of the single U-bolts shown 125

in Figure 12. These bolts have two legs 86, 87 with the unusual nuts 88, 89, and in this instance lead washers 90, 91 are used to prevent leakage. Between the legs of the U-bolt it has a raised portion as shown at 92 to provide fastenings to be made to the hanger wherever necessary.

Ordinarily the flat plates 93 are used as illustrated in Figure 7 to hold the edges of the plates down firmly, but whenever it may be desired to attach a fastening to the plates 94 with the raised portion 95 may be used.

The U-bolts are fastened to the cables as illustrated at 96 and they pass through the edges of two of the metal sheets, the overlap being sufficient to prevent the ingress of rain. Such of the plates as may be desired are provided with an opening around which is a rectangular flanged guide 81' to receive slides 81". When the weather is good the slides may be completely removed, but if it is desired to have ventilation while at the same time providing against the ingress of rain, the slides will be placed in position and will shed the rain.

The braces extending from the corner posts to the center posts consists of two channel irons 98, 99 bolted to a suitable heavy flat plate 100—see Figure 14.

What I claim is as follows, but various

modifications may be made in the construction shown in the drawings and above particularly described form, within the purview of my invention.

1. In a structure of the class described, comprising masts carrying a plurality of tension trusses supporting a plurality of intermediate cables, a plurality of overlapping metal sheets forming the roof and side walls of the hanger, U-clamps along the edges of the plates for securing the plates to the cables and a retaining plate through which the U-clamps pass and which bear on the side walls. 45

2. In a structure of the class described, a plurality of posts, outriggers to stiffen the posts, cable tension trusses, connecting the posts in two directions, the upper chord of the truss being higher at the posts than 50 at the center of the truss, other lower posts to support the structure intermediate the first posts, cables crossing each other, means to connect the cable crossing, means to secure a sheet structure to the crossed cables 55 with the edges of the sheet structure overlapping and means to stay the structure from the ground.

In testimony whereof I have hereunto set my hand this 17th day of January, A. D. 60 1922.

FREDERICK J. LUEBBERT.
